UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Application filed October 14, 1929. Serial No. 399,506.

My invention relates to heat exchange devices and has to do more particularly with devices which are particularly adapted to heat enclosures such as rooms in a dwelling house, or the like.

An object of my invention is to provide a device of the type referred to which will effect an efficient exchange of heat to air and induce a circulation of such air into an enclosure such as a room, or the like, with a minimum of friction.

Another object is to provide such a device which may be built up of a plurality of similar units to any desired size depending upon the heat requirements of a given situation, and to construct the device so that heating of the room is accomplished by connection and direct contact with the device.

Many other objects and advantages of the kind described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts;

Fig. 1 is an elevational view of a heating device embodying my invention mounted in a wall of a room, the wall being shown fragmentarily;

Fig. 2 is a sectional view taken on line 2—2 of Fig. 1;

Fig. 3 is a sectional view taken on line 3—3 of Fig. 2;

Fig. 4 is a sectional view taken on line 4—4 of Fig. 2;

Fig. 5 is an elevational view similar to Figs. 1 and 5 and showing still another embodiment of my invention;

Fig. 6 is a sectional view taken on line 6—6 of Fig. 5;

Fig. 7 is a sectional view taken on line 7—7 of Fig. 5;

Fig. 8 is a front elevation of another modification of which the invention is susceptible;

Fig. 9 is a section taken on line 9—9 of Fig. 8; and

Fig. 10 is a section taken on line 10—10 of Fig. 8.

Referring first to the embodiment shown in Figs. 1 to 4, inclusive, I have shown a heating device indicated generally at 10 in Fig. 55 mounted in a recess 12 formed in a wall 13 of a room and disposed under a window 15. Obviously, the heating device 10 may be disposed in various other arrangements in the wall, and I am not to be limited to any specific arrangement. 60

The heating device 10 comprises a plurality of similar units 16, of which three are shown, although it will be readily apparent that any suitable number of units 16 may be mounted in a given installation depending upon the particular heat requirements. Each of the units 16 comprises a hollow leg portion 18 having a front wall 19 and a rear wall 19' and normally disposed with its longitudinal 70 axis in a substantially vertical plane as shown in Fig. 2, the leg being in communication with a hollow foot member 20. The foot members 20 comprise a plurality of laterally projecting box-like members 22, having 75 spaces 23 therebetween. Arranged in the spaces 23 between the members 22 are corrugated members 25. These members 25 may be formed of any suitable heat conducting material, such as sheet iron, galvanized iron 80 or the like, and are so bent and arranged as to extend substantially the entire distance between the members 22 so as to make a good contact therewith at each bend 26 and are of sufficient depth to extend substantially from 85 top to bottom thereof.

A conduit 27 is provided for the inlet to the device 10 of heat exchange fluid which fluid is preferably steam although hot water may be used, if desired. The conduit 27 communicates by means of an elbow 28 with the one of the endmost units 16 and a drain pipe 30 communicates by means of an elbow 31 with the last unit 16 of the series. 90

It will be noted that a substantially cylindrical portion 33 is formed at the upper portion of the leg members 18 which communicates therewith, and that a rod or bolt 35 extends through the cylindrical portion 33 and may be threaded through spiders 36 formed 100

in the cylindrical portion for retaining the units in fixed relation. At the opposite end of the leg members 18 and communicating therewith, are cylindrical portions 38 which are somewhat depressed from the level of the foot members 20 so as to serve as drains therefor. Rods 40 extend through the cylindrical portion 38 and are in threaded engagement with spiders 42 formed therein. A plurality of push nipples 44 is provided for effecting fluid tight connections between the various members 16, these push nipples being seated in the ends of the cylindrical portions 33 and 38.

When devices embodying my invention are mounted in a recess of a wall, as shown in Fig. 1, a space 45 is preferably provided at the bottom thereof, and another space 46 at the top thereof. When steam is used as the heat exchange fluid it is preferably introduced through the conduit 27, the condensate draining into the tubular members 38 and passing out of the heating unit through the conduit 30. Obviously, if hot water is used as the heat exchange fluid, it may be introduced through either one of the conduits.

When the device has been heated by means of any suitable fluid, air will be induced to flow into the recess 12 of the wall through the space 45 and upwardly through the foot member 20. In passing through the spaces 23 between the box-like members 22 of the foot member, the air will be divided into a plurality of columns by means of the corrugated members 25. Inasmuch as the members 25 are of heat conducting material and are in effective contact with the member 22 at a plurality of points 26, they will thus be maintained at substantially the same temperature as the members 22 and hence the air will be very effectively warmed by contact with the walls of the members 25 as well as by the members 22. After passing through the foot like members 20 the air will flow upwardly through the recess 12 and will pass in contact with the surface of the rear wall 19 of the leg members 18, thus effecting a further heat exchange. The air will then flow through the space 46 and out into the room.

Referring now to the embodiments of Figs. 5 to 7, there is shown here a heat exchange unit indicated generally at 70 and arranged in a recess 71 in a wall 72 substantially in the same manner as in the other embodiments. The unit 70 comprises a tank 73 having walls 74 and 74' arranged in substantially a vertical plane and communicating with conduits 75 and 76 which may be used as an inlet and outlet respectively for heat exchange fluid. Adjacent the lower portion of the tank 73, so as to extend laterally therefrom and communicating therewith is a plurality of tubes 78, formed of heat conducting material such as metal. As best shown in Fig. 7, these tubes are prefer-

ably U-shaped, the legs of the U's being relatively short and the web of the U's being relatively long. Obviously, this shape is preferred merely for the purpose of economy of space and any other suitable configuration may be adopted, if desired. The tubes 78, as shown in Fig. 7 are arranged concentrically and may also be arranged in parallel relation, as shown in Fig. 6. Thus, in the particular embodiment shown, 70 nine tubes 78 are utilized. However, it will be readily apparent that any convenient number may be used, and furthermore, the tubes 78 may be disposed in various other arrangements with reference to each other, 75 and the particular arrangement shown is to be considered as only exemplary.

A plurality of heat conducting vanes or fins 80 of heat conducting material is provided on the tubes 78 and these fins may be 80 secured by soldering, welding, or the like.

When a heat exchange fluid is introduced into the unit 70, a current of air will be induced to enter the recess 71 through the space below the tank 73 and to flow upwardly past the tubes 78. The air will make effective heat exchanging contact with the tubes 78 and with the fins 80 and will then flow upwardly through the recess 71 and in contact with the rear wall 74' of the tank 95 73, thence flowing out of the recess through the space above the tank 73 and into the room.

In the embodiment of the invention illustrated in Figs. 8 to 10, the portion 82 which corresponds in function to the leg member 18 of the structure shown in Fig. 1 has its front face formed to provide a plurality of corrugations 83 which will increase the heating surface presented by this portion of the 100 device and allow for contraction and expansion. This leg member is formed of a sheet of material bent upon itself having its front face constructed as just referred to and is provided with a rear wall 84, it being understood 105 that the ends of the sheet of which this portion is formed are braced or otherwise secured together to form front and rear walls of the chamber 85. As clearly shown in Fig. 10, the chamber is completed through 110 the agency of the end walls 86-86. A fluid supply pipe 87 is connected with the upper end of the chamber and a drain connection 115 88 is provided which connects with a U-shaped hollow element 89, the opposite ends 90 and 91 of which are connected and communicate with the element having the chamber 85. This U-shaped element is arranged at the lower end of the chamber and by virtue of its U-shaped construction provides a 120 space between a wall of the chamber 85 and the connecting passage 92 in which space a plurality of heat exchange fins 93, 94 and 95 are located. Certain of said fins are connected with the element having the chamber 125 130

85 whereas others thereof such as 100, 101 and 102 are connected to and project from the U-shaped member 89. This structure including the chambered element 85 and the

hence, I do not wish to be understood as limiting myself to the exact form, construction, arrangement, and combination of parts herein shown and described or uses mentioned.

5 U-shaped member 89 is designed to be arranged in a casing 96, the casing and member being disposed relatively to each other to provide a space 97. Heat radiating fins such as 99, 100 and 101 are located in the .10 space 97 provided between the member forming the passage 92 and the wall 98 of the casing. Heat radiating fins 102, 103 and 104 extend from the opposite side of the element providing the passage 92. It will be .15 noted that the U-shaped element 89 and these fins are arranged in the lower portion of the casing 96 in spaced relation to the lowermost end of the casing and thus air entering the casing at this point passes between and contacts with the tubular passage 89 and said fins is caused to travel upwardly through the casing by convection and escapes from the casing through the opening 105. The casing 96 is provided with a .20 curved wall 106 which is soldered or otherwise secured to the rear wall 98 of the casing and is provided with a flange 107 which produces a water containing chamber 108, the latter of which is closed by a removable .25 cover 109. The water contained in the chamber 108 will become heated, escape from the chamber and act to humidify the air contained in the room in which the heat exchange device is located. A damper 110 .30 is arranged in the casing 96 and is provided to permit or prevent the flow of air through the chamber between the wall 98 and the wall 84 of the heat exchange device.

In all of the embodiments shown, it will .35 be readily apparent that a very large area of heating surface is provided for the air, while, at the same time, there is a minimum of friction to impede the flow thereof. Furthermore, the air is caused to pick up a relatively large amount of heat while flowing through a relatively short distance, that is, through the channels of the member provided adjacent the base of the various units disclosed. Due to the expansion thereof, the .40 rate of flow of the air is thus greatly increased, improving the circulation thereof, and hence, its heat exchanging efficiency. In flowing upwardly through the recess it is not permitted to cool appreciably inasmuch .45 as it is maintained in contact with the vertical member shown in the various embodiments. The air is thus caused to flow out into the room at a relatively high velocity and temperature, substantially none of the .50 heat having been lost before the air enters the room.

Having thus described my invention, it is obvious that various immaterial modifications may be made in the same without departing from the spirit of my invention;

What I claim as new and desire to secure by Letters Patent is:

1. In a device of the class described, a substantially vertical tank-like member elongated in cross section, and a base member extending along an edge of said tank-like member and communicating with said tank-like member, said base member having a plurality of heat exchanging channels extending entirely therethrough.

2. In a device of the class described, a substantially vertical tank-like member elongated in cross section, and a base member communicating with said tank-like member, said base member comprising a plurality of laterally extending spaced hollow members extending transversely of said tank-like member along one edge thereof.

3. In a device of the class described, a substantially vertical tank-like member, a base member communicating with said tank-like member, said base member comprising a plurality of laterally extending spaced hollow members, and heat conducting vanes arranged on said hollow members.

4. In a device of the kind described, the combination of a hollow member having an inlet and an outlet, hollow elements which communicate with said first mentioned hollow member, said hollow elements being spaced from each other to provide air passages and said hollow elements being disposed along the lower portion of said hollow member and providing a space above said elements with which said air passages communicate.

5. In a device of the kind described, the combination of a hollow member having an inlet and an outlet, hollow elements which communicate with said first mentioned hollow member, said hollow elements being spaced from each other to provide air passages and said hollow elements being disposed along the lower portion of said hollow member and providing a space above said elements with which said air passages communicate, and heat radiating fins located in said space between said hollow elements.

6. In a device of the kind described, the combination of a hollow member of elongated cross section having an inlet and an outlet, hollow elements arranged transversely of said first mentioned hollow member which communicate with said first mentioned hollow member, said hollow elements being spaced from each other to provide air passages and said hollow elements being disposed along the lower portion of said hollow member and providing a space above said elements with which said air passages communicate.

7. In a device of the kind described, the combination of a hollow member elongated in cross section having an inlet and an outlet, a hollow element communicating with said 5 first mentioned hollow member, said hollow element projecting from one side of and being disposed along one edge of the hollow member and cooperating with said hollow member to respectively define a side and end of a 10 space above said element.

8. In a device of the kind described, the combination of a hollow member elongated in cross section having a fluid inlet and a fluid outlet, said elongated member having an off- 15 set portion adjacent the lower end thereof and providing hollow laterally projecting elements which communicate with said portion of elongated cross section, said offset portion having passages arranged transversely to 20 said offset portion providing air passages.

In witness whereof, I hereunto subscribe
my name this 7th day of October, A. D. 1929.

ARTHUR B. MODINE.
